US00D579952S

(12) **United States Design Patent**
Yamada

(10) **Patent No.:** **US D579,952 S**
(45) **Date of Patent:** **** Nov. 4, 2008**

(54) **AUDIO PLAYER**

(75) Inventor: **Yoshinori Yamada**, Tokyo (JP)

(73) Assignee: **Sony Corporation**, Tokyo (JP)

(**) Term: **14 Years**

(21) Appl. No.: **29/269,455**

(22) Filed: **Dec. 1, 2006**

(30) **Foreign Application Priority Data**

Aug. 29, 2006 (JP) 2006-022790

(51) **LOC (8) Cl.** **14-03**

(52) **U.S. Cl.** **D14/496**

(58) **Field of Classification Search** ..... D14/496, D14/401, 435, 474, 483, 217, 137, 138, 160, D14/168; 345/156, 169, 173-179, 905; 715/727-729, 715/864; 455/11.1, 773, 344-347, 93, 95; 370/342-344; 369/1, 2, 6, 12; 463/43-47; 273/148 B

See application file for complete search history.

(57) **CLAIM**

The ornamental design for an audio player, as shown and described.

DESCRIPTION

FIG. 1 is a perspective view of an audio player showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines, which define the bounds of the claimed design, form no part thereof. The broken lines environmental are for illustrative purpose only and form no part of the claimed design.
